SOUND-TRANSMISSION, SOUND-RECORD-
ING, AND SOUND-REPRODUCING SYS-
TEMAlan Dower Blumlein, West Ealing, London, Eng-
land, assignor to Electric & Musical Industries
Limited, Hayes, EnglandApplication November 8, 1934, Serial No. 752,147
In Great Britain February 10, 1934

6 Claims. (CL. 179—1)

This invention relates to systems for the electrical transmission of sound, and comprises an improvement in or modification of the invention disclosed in the specification of application No. 647,057 filed the 13th day of December, 1932. In that earlier specification are shown systems in which sounds are picked up by a plurality of microphones for transmission in such a manner that when reproduced the sounds convey a binaural impression to a listener. In the systems described the microphones are of the same kind in each case, e. g. two or more velocity microphones, or two or more pressure microphones.

The present invention consists in a system of sound transmission wherein impulses picked up by a plurality of microphones are reproduced by a plurality of loud speakers, comprising, for use together, a velocity microphone or microphone element and a pressure microphone or microphone element.

The arrangement may consist in the combination of a velocity microphone and a pressure microphone which are built separately from one another, or the microphone elements may be built together (e. g. with a common magnetic field system) so as substantially to form together a single piece of apparatus. One device of the latter form has been described in the Journal of the Acoustical Society of America, Volume V, page 139 et seq., October, 1933, and different forms of the present invention may be variously regarded as a modified use of such a device in a system such as described in application No. 647,057 filed the 13th day of December, 1932, or as a system such as previously described in application No. 647,057 filed the 13th day of December, 1932, embodying one or more microphones of that character in place of the microphones originally indicated. Alternatively there may be employed in accordance with the present invention other forms of microphones embodying combined velocity-responsive and pressure-sensitive elements, different from that described in the above-mentioned publication.

The invention will be readily understood from the following description of a few forms which it may assume, but it must be understood that these forms are described merely by way of illustration and not of limitation to the scope of the invention. Understanding of the description will be facilitated by reference to the accompanying drawings representing arrangements in accordance with the invention.

In these drawings:—

Figures 1 and 2 represent two forms of the invention in symbolic fashion:

Figures 3 to 6 represent diagrammatically one form of an arrangement previously described in the specification of U. S. A. patent application No. 647,057 of 13th December, 1932, and

Figures 7 and 8 represent front and side elevations respectively of a form of known compound microphone which may be used in a novel manner in connection with the present invention.

In carrying the invention into effect in one convenient manner a sound transmission system is arranged whereby sound impulses picked up by a plurality of microphones are transmitted over suitable channels and reproduced in a plurality of loud speakers, substantially as described in application No. 647,057, filed the 13th day of December, 1932. The system may incorporate recording and reproducing stages, and the transmission is not necessarily over telephone or like lines but may, for example, be effected by duplex wireless telephony.

To facilitate understanding of the present specification a brief description of the invention described in the above mentioned prior specification will be given. One arrangement of that invention is shown in Figures 3 to 6 herein. Sounds from a source *s* are picked up by two pressure microphones *a*₁, *a*₂, amplified if necessary by amplifiers *b*₁, *b*₂, passed through interacting

networks *c*₁ (described more fully below), the outputs again amplified if necessary by amplifiers *d*₁, *d*₂, and fed to loud speakers *e*₁, *e*₂. The interacting networks *c*₁ include initially an arrangement of transformer windings shown in Figure 4 so arranged that their outputs comprise respectively half the sum and half the difference of the inputs. Such an arrangement may be represented diagrammatically by the symbol shown in Figure 5. Figure 6 represents the complete network arrangement *c*₁ of the circuit shown in Figure 3, and it will be seen that after passing through transformer windings *x* the impulses pass through networks comprising, in one channel the resistances *g*₁, *h*₁ and *i*₁, and in the other channel resistances *d*₄, *e*₄ and *k*₄, and condenser *f*₄.

The modified impulses are again passed through transformer windings *y* (whereby half their sum and half their difference is again obtained), and fed to the amplifiers *d*₁, *d*₂ and loud speakers *e*₁, *e*₂. It is shown in the prior specification referred to that by suitable choice and arrangement of the elements in this circuit a directional sound effect is conveyed to a listener by the loud speakers *e*₁, *e*₂ depending upon the di-

rection of the sound source S_1 relatively to the microphones a_1, a_2 .

According to the present invention the transmitting microphones a_1, a_2 may be replaced by a 5 velocity microphone, such as a moving strip microphone, in close juxtaposition to a pressure microphone, such as a carbon or crystal microphone. While the invention is not limited to these two forms of microphone (i. e. moving strip 10 and carbon or crystal) they are mentioned in view of the fact that they can be made of very small dimensions which allow them to be brought close together. These two microphones are 15 connected together so that their outputs are fed to two channels leading to later stages of the system, and the arrangement is such that one of these channels receives and transmits the sum of the microphone outputs while the other receives their difference. Any convenient arrangement 20 of electrical elements may be used to provide this sum-and-difference step, and several arrangements will be found described in the above-mentioned specification and one such arrangement is shown in Figs. 4 and 5 and described 25 above.

The outputs so obtained after this summing and differencing process consist of currents which for a particular sound source are in phase but whose relative magnitudes depend on the direction 30 of the sound wave arriving at the microphone, and these can be made suitable for obtaining the desired binaural effect by arranging the velocity microphone to be insensitive to sound arriving from the "central" direction, so that outputs are obtained from microphones 35 which are equivalent to the outputs of the first "sum" and "difference" channels x (Fig. 6 herewith).

For example, with such an arrangement the 40 output of the pressure microphone (after amplification or attenuation) is comparable with the output obtained from the resistance h_4 shown in Fig. 6 herewith (corresponding to Figure 5 of application No. 647,057, filed the 13th day of December, 1932) while the output from the velocity microphone is comparable with the output obtained from the resistance e_4 of that figure, and by providing the above-mentioned sum-and-difference process once only to these microphone 45 impulses, therefore, outputs are provided suitable for feeding to the loud speakers.

The transformer arrangement x and the modifying networks comprising elements $d_4, e_4, f_4, g_4, h_4, i_4$ and k_4 shown in Figure 6 can therefore be 50 eliminated and a much simpler arrangement is available giving the same effect.

This will be seen clearly by referring to Figure 1 wherein a represents a directionally sensitive velocity microphone, e. g. a strip microphone, 55 while b represents a pressure microphone, which is not directionally sensitive. These are connected to a network represented at c by the symbol introduced in Fig. 5 herewith (corresponding to Figure 4 of application No. 647,057 filed the 13th day of December, 1932), and the outputs pass through leads d and e to two loud speakers. The strip of microphone a is arranged along the axis of the sound field and is clearly insensitive to sounds from a sound source S_1 on that axis, 60 but has maximum sensitivity to sounds from a lateral source S_2 , whereas the sensitivity of microphone b is substantially independent of the position of the source. Leads d and e transmit respectively half the sum and half the difference 65 of the microphone outputs, and clearly with the

sound source in position S_1 the two outputs in leads d and e are the same (so that loud speakers connected thereto would be equally loud and indicate correctly a central position of the sound source) whereas with the sound source in position S_2 the microphone outputs are the same, and the impulses in leads d and e are therefore respectively a maximum value and zero (which provides full sound in one loud speaker and substantially none in the other, thus giving the correct impression of a laterally displaced sound source).

An alternative arrangement of the present invention which may be used (especially where the microphones are of similar impedance, as in the case of microphones having two strip elements, described more fully below) is shown in Figure 2 and consists in connecting one terminal of one microphone to one of the other microphones and connecting the other microphone terminals respectively to opposite ends of the primary winding f of a transformer. The primary g of a second transformer is connected between the common microphone terminals and the mid-point of the first-mentioned transformer primary f , and it will be clear that while the output from the secondary of one transformer will consist in the sum of the microphone impulses that from the other will consist in their difference. By suitably arranging the orientation of the microphones (one of which is, of course, directionally sensitive), and by suitably choosing the transformer ratios in order to obtain the desired ratio of outputs in the two channels connected to the secondary windings of the transformers, the impulses can be controlled satisfactorily to provide the binaural effect aimed at by the system, and the relative amplitudes of impulses in the two channels determined in accordance with the direction from which the sounds reach the microphones.

Instead of employing two separate microphones, the microphone elements may be arranged together to form a single instrument. An instrument of such a character has been described in the Journal of the Acoustical Society of America, Volume V, page 139 et seq., October, 1933, and also the specification of British Patent No. 405,497, and as shown in Figs. 7 and 8, comprises a strip a_3 supported from its ends between poles of a field magnet b_3 and having midway along its length a supporting bridge c_3 which effectively divides the strip into two separately operative portions, one of which is allowed to function as an ordinary velocity sensitive element, while the other is loaded on one side by an acoustic impedance (consisting of an adjacent tube d_3 packed with felt absorption pads) whereby it is rendered sensitive to pressure variations and substantially non-directional. Such a microphone may readily be employed in the present invention, the elements being arranged and electrically connected in the manner described above. Alternatively the microphone may be slightly modified to meet the requirements of this invention. For example instead of being formed of one strip two separate elements may be located between the magnetic pole pieces side by side and substantially parallel to one another, one being acoustically damped as indicated above, this arrangement allowing relative angular displacement of the planes of the elements, should that be necessary or desirable to achieve the desired object.

As previously described in the above-mentioned

publications a microphone of this character is employed as a single receiving device, the impulses from the two elements in series being transmitted together as a single output. If such a microphone is used in the present invention each element is treated as a separate microphone, and the separate outputs are caused to interact in the manner shown, for example, in Figure 2.

Any of the systems described herein may be employed in respect of only part of the frequency range being transmitted. For example in copending application No. 750,898, filed October 31, 1934, it is shown that in some circumstances it is desirable initially to transmit low frequencies over one pair of channels and high frequencies over another pair of channels, and the systems described in this specification may if desired be employed for one part of the range, in combination with a different system or systems for another part or parts of the range.

Finally it must be understood that the invention is not limited solely to the details of construction or arrangements described herein since modifications may be introduced as they become desirable or necessary in order to carry the invention into effect under different conditions and requirements which have to be fulfilled, without departing in any way from the scope of the invention.

Having now described my invention, what I claim as new and desire to secure by Letters Patent is:—

1. A system of sound transmission comprising a plurality of loud speakers, a velocity microphone element and a pressure microphone element, a plurality of channels connecting said microphone elements to said loud speakers, and means by which the impulse transmitted in one channel is composed of half the sum of the microphone outputs while the impulse transmitted in another channel is composed of half the difference of the microphone outputs.

2. A system of sound transmission according to claim 1 comprising transformers in one of which the microphone outputs assist, and in another of which the microphone outputs oppose, one another.

3. A system of sound transmission comprising

ing a plurality of loudspeakers, a velocity microphone element, and a pressure microphone element, and a plurality of channels, connecting said microphone elements to said loudspeakers, so arranged that the output intensities of the loudspeakers differ from one another by an amount dependent upon the output of the velocity element and their relative output intensities vary in accordance with the direction from which the sounds are incident upon the microphone elements.

4. A system of sound transmission comprising a velocity-sensitive microphone element and a pressure-sensitive microphone element arranged in close juxtaposition, means for causing the output channels of said microphone elements to interact with one another, and a plurality of loudspeakers connected to receive impulses resulting from said interaction of the microphone outputs, the arrangement being such that the loudspeaker outputs differ by an amount proportional to the output of the velocity microphone, and the relative intensities of the loudspeakers vary in accordance with the direction from which the sounds approach the microphones.

5. A system of sound transmission comprising a velocity-sensitive microphone element and a pressure-sensitive microphone element arranged together in a single instrument, each element being connected to the transmission circuit as a separate microphone, a plurality of loudspeakers by which impulses from said microphones are reproduced, and means adapted automatically to control the relative intensities of said loudspeaker outputs in accordance with the direction from which the sounds to be transmitted reach said microphone elements.

6. In a system of sound transmission according to claim 5 a microphone comprising, in a single instrument, a strip element sensitive to the velocity of the air due to the sounds received, and another strip element acoustically loaded to render it sensitive to pressure variations of the air due to the sounds received, each element being connected to the transmission circuit as a separate microphone.

ALAN DOWER BLUMLEIN.
